LAMINATED PADLOCK

Daniel J. Foote, Wauwatosa, Wis., and Harry E. Soref, deceased, late of Milwaukee, Wis., by Milton Soref, administrator, Milwaukee, Wis., assignors to Master Lock Company, Milwaukee, Wis., a corporation of Wisconsin

Original application October 27, 1955, Serial No. 543,182. Divided and this application July 16, 1957, Serial No. 672,167

1 Claim. (Cl. 70—38)

This invention relates to improvements in laminated padlocks, and more particularly to an improved shackle plate incorporated in the laminated body of a padlock, and is a division of application Serial No. 543,182, filed October 27, 1955, now abandoned.

A primary object of the present invention is to provide, in a padlock of the character described, a shackle plate provided with simple and effective means for movably anchoring the extended end of a shackle.

Heretofore, in the manufacture of padlocks it has been the practice to anchor the extended leg of the shackle in the padlock body by means of a pin within the padlock body but this has presented problems in the assembly of the padlock. When a pin is utilized for engaging the extended end of the shackle, the pin which is loosely held within the padlock body, offers only a relative slight amount of engagement with the shackle and will therefore be susceptible of wear during constant use of the padlock when pressure is exerted on the shackle. The pin utilized is relatively small and it is furthermore a slow and cumbersome task to accurately mount the same within the padlock body, and the pin method of anchoring the extended leg of the padlock shackle does not readily lend itself for use in connection with a laminated padlock wherein the body is composed of a series of superimposed plates.

The present invention obviates the objections noted in connection with a shackle engaging pin by the utilization within the padlock body of an apertured plate having a depending annular collar which is bumped to prevent withdrawal of the shouldered end of the extended leg of the padlock shackle after the assembly operations have been completed. In the present invention, instead of the utilization of a member affording only limited engagement as between the shackle leg and the anchoring member within the padlock body, a specially constructed shackle plate is provided which forms one of the laminations of the padlock body and which is provided with a flanged opening to form a substantial wall of metal entirely around the shackle leg and which is finally bumped to alter its shape and reduce its size to prevent withdrawal of the shouldered end of the shackle leg but retaining firm and substantial engagement with the shackle leg throughout its circumference, the connection being one which cannot become impaired through wear and usage.

A further object of the invention is to provide, in a laminated padlock, a heavy shackle leg encircling ring which easily receives the shackle leg during assembly and which is thereafter distorted to movably retain the extended leg of the shackle within the lock body.

A further, more specific object of the invention is to provide, in a laminated padlock, a shackle plate having a shackle leg receiving opening therein surrounded by a relatively deep collar which forms an extended guide for the shackle leg as it moves inwardly and outwardly relative to the padlock body during operation of the padlock.

2

A further, more specific object of the invention is to provide, in a padlock of the class described, a shackle plate having a shouldered opening therein through which the shackle leg extends and which provides a smooth bearing for movement of the shackle leg which will improve with wear and which will withstand deformation and strain during repeated operations of the padlock.

With the above and other objects in view the invention consists of the improved laminated padlock, and its parts and combinations as set forth in the claim, and all equivalents thereof.

In the accompanying drawing in which the same reference characters indicate the same parts in all of the views:

15 Fig. 1 is a side view of a laminated padlock with a portion thereof broken away and in section to show the manner in which the extended leg of the shackle is movably anchored;

20 Fig. 2 is an inverted plan view of the shackle plate before deformation of the collar surrounding its shackle leg opening;

Fig. 3 is an end view of the plate shown in Fig. 2; and Fig. 4 is a fragmentary detail sectional view taken on line 4—4 of Fig. 1.

25 In the type of padlock construction to which the present invention pertains, a strong body or casing is provided by superimposing a plurality of sheet metal plates 8 which are formed with aligned openings serving to provide the required recesses and chambers in the body or casing 30 and which are permanently assembled in laminated relation by means of connecting pins 9. In addition to the intermediate plates 8 there will be in the assembly a top plate 10, a bottom plate 11, and a shackle plate 12, the shackle plate 12 being specially formed and being 35 substantially midway between the top and bottom plates 10 and 11 in the assemblage.

The padlock also includes a U-shaped shackle 13 which customarily has a short leg 14 and a long leg 15, the latter being accommodated in a socket in the casing which 40 is formed by aligned openings in the plates 8 and 10, and also by the opening 16 in the shackle plate 12, which opening 16 is originally of circular contour and is surrounded by a relatively deep collar or flange 17 which projects substantially below the undersurface of the 45 plate 12.

The long leg 15 of the shackle 13 has its inner end reduced as at 15' with the inner extremity thereof being formed with an enlarging collar or shoulder 18. The opening 16 in the plate 12 is originally of sufficient diameter to just permit the passage therethrough of the shouldered extremity 18 of the shackle leg 15, and the shouldered opening 16—17 of the shackle plate 12 is of somewhat less diameter than the openings in the superimposed plates 8, except that the plate 8' immediately inwardly of the plate 12 may have a slightly enlarged opening so as to receive therewithin the flange or collar 17 of the plate 12 in its original form. It will be observed from Fig. 2 that the end of the shackle plate 12 adjacent its shouldered opening has a slight outward off-set 12' 60 which in the initially assembled relation of the various plates projects outwardly slightly beyond the adjacent plates 8 and 8'. Also, said end portion of the plate 12 has eccentrically shaped openings 20 therein extending to peripheral portions of the opening collar 17 and which leave a web of metal 21 which extends from the collar 17 to the end off-set 12' of the plate 12.

After the various plates 8, 8', 10, 11 and 12 have been assembled in superimposed body forming relationship and the long leg 15 of the shackle is passed into the cavity formed by the aligned plate openings, the projecting end portion 12' of the plate 12 is subjected to a bumping operation by a kick press which is effective to drive

the plate portion 12' into registration with the ends of the other plates, which then, through the metal web 21, applies inward pressure to and deforms inwardly a side portion of the collar 17 surrounding the opening 16, to the shape shown in Figs. 1 and 4, and the deformed condition of the collar is then such as to provide a shoulder which will engage the enlarged end 18 of the shackle leg 15 upon outward movement of the shackle to prevent undesired withdrawal of the shackle leg 15 from the assemblage. The deformation of the collar is facilitated by the fact that the metal of the plate 12 can shift around the adjacent plate connecting pins 9 which are accommodated by off-set recesses in the plate openings 20.

In the locked condition of the assemblage the shackle 13 is thrust into the casing with the extremity of its short leg 14 entering an opening therefor in the padlock body, as seen in Fig. 1.

When a key (not shown) is inserted into the lock and turned, the notched short end of the shackle is released in the conventional manner as shown and described in Patent No. 2,352,190, for instance. A coiled spring 19 associated with the inner extremity of the long leg 15 of the shackle then urges the shackle outwardly relative to the casing cavity to an extent to remove the notched end of the short leg 14 completely out of the casing to permit turning movements of the padlock shackle. The movement of the long leg of the shackle relative to the casing is limited by the engagement of the enlarged end 18 of the shackle leg 15 with the deformed collar 17 of the shackle plate 12 so that complete withdrawal of the long leg of the shackle from the casing is prevented but the deformed collar 17 completely surrounds the reduced portion 15' of the shackle leg and provides a cylindrical bearing surface of substantial depth which cannot work loose or become impaired by wear. In fact, continued longitudinal movement of the shackle portion 15' within the collar 17 will smooth and polish the engaging bearing surfaces and improve the operation of the padlock.

From the foregoing description it will be seen that the reduced portion 15' of the long shackle leg is actually at all times encircled by a heavy band of metal which forms a stop upon outward movement of said shackle leg. The strength and life of the laminated padlock is greatly enhanced thereby and it will further be evident that the assembly of the laminated padlock casing is extremely

simple as the various plates are merely secured together in superimposed relation and the cavity therein receives the long leg 15 of the shackle which can have its enlarged end portion 18 originally easily passed through the collared opening 16 in the shackle plate 12. Thereafter a simple bumping operation is effective to deform and reduce the diameter of the collar 17 which thereafter engages the shackle leg enlargement 18 to form a stop shoulder against complete outward withdrawal of said shackle leg.

The improved laminated padlock is simple, inexpensive and well adapted for the purposes set forth.

What is claimed as the invention is:

A laminated padlock casing comprising a plurality of superimposed plates having aligned circular openings therein which form a cavity transverse to the planes of the plates, a first intermediate plate having the opening of greater circumference than those of the plates there-adjacent; a second intermediate plate having a relatively deep, annular collar of eccentric contour surrounding its opening and projecting beyond a face of said plate into the opening in said first intermediate plate, a shackle leg extending into the cavity formed by the plate openings and having a reduced portion of circular cross-section within and completely surrounded by the collar of the second intermediate plate; an extremity of the reduced portion being shouldered; a portion of the collar of the second intermediate plate being offset inwardly into the cavity in an arc to embrace a substantial surface portion of the reduced portion of the shackle leg, said offset portion of the collar together with the adjoining collar portion forming an annular eccentrically shaped stop of greater thickness than said plate for engagement with the shouldered portion of the shackle leg to limit axial movement of the shackle leg relative to the casing cavity.
